LAY CYCLE CAGE APPARATUS

Gerald L. Kitson, 9709 Belding Road,
Rockford, Mich. 49341

Filed Mar. 12, 1971, Ser. No. 123,932

Term of patent 14 years

Int. Cl. D30—02

U.S. Cl. D30—1

FIG. 1

FIG. 1 is a top perspective view of a lay cycle cage apparatus showing my new design;

FIG. 2 is a fragmentary end elevational view partly in cross-section with the feed-pipe supports and conveyor belt omitted for convenience in illustration; and

FIG. 3 is a fragmentary top perspective view thereof with one of the doors in opened position.

I claim:

The ornamental design for lay cycle cage apparatus, as shown and described.
